DESIGN FOR A DISPENSING CARTON

Alessandro H. Sumbardo, Seattle, Wash., assignor to Dermetics, Inc., Seattle, Wash.

Application December 13, 1943, Serial No. 112,001

Term of patent 14 years

(Cl. D58—12)

To all whom it may concern:

Be it known that I, Alessandro H. Sumbardo, a citizen of the United States, residing at Seattle, in the county of King and State of Washington, have invented a new, original, and ornamental Design for a Dispensing Carton, of which the following is a specification, reference being had to the accompanying drawing forming a part thereof.

I claim:

The ornamental design for a dispensing carton, as shown.

ALESSANDRO H. SUMBARDO.
